WILLIAM DUNCAN, OF LEBANON, NEW HAMPSHIRE.

Letters Patent No. 87,095, dated February 23, 1869.

IMPROVEMENT IN DOOR-SPRING.

The Schedule referred to in these Letters Patent and making part of the same.

To all whom it may concern:

Be it known that I, WILLIAM DUNCAN, of Lebanon, in the county of Grafton, and State of New Hampshire, have invented a new and useful Device for Shutting Doors; and I do hereby declare that the following is a full and exact description of the same, reference being had to the accompanying drawings, and to the letters of reference marked thereon.

This invention relates to a simple device for shutting doors, gates, &c., and consists mainly in the employment of a screw and nut, in connection with a spring or weight, the arrangement being such that when the door is opened the screw is turned, and the nut thus forced upward against the pressure of the weight or spring; consequently, when the door is left free to close, the spring or weight, acting upon the nut, causes the screw to revolve and shut the door.

The details of construction and manner of operation will be fully described hereinafter.

In the drawings—

Figure 1 is a perspective view of my invention attached to a door.

Figure 2, a side elevation of another form of the invention, with portions broken away to show the construction.

To enable others skilled in the art to make and use my invention, I will proceed to describe fully its construction and operation.

A represents a plate, which is provided with the slot *a* and ears *a' a'*, as shown.

B represents a shaft, or rod, resting in bearings in the ears *a' a'*, which has at its lower end, beneath the bearing, the arm *b*, which is rigidly secured to it in any suitable manner.

This shaft is also provided, near its lower end, with the screw-threads *b'*, of sharp pitch, and near its upper end with the screw-threads *b''*, of ordinary pitch.

Upon these latter threads turns the nut *B'*.

C represents a nut, turning upon the threads *b'*, as shown.

This nut is provided with a projection, *c*, which fits snugly into the slot *a*.

D represents a coiled spring, which encircles the shaft *B*, between the nut *C* and *B'*. Instead of this spring,

weights may be used to press against the nut, as is shown in fig. 2.

The operation is as follows:

The device having been suitably attached to the casing, in any proper position, the arm *b* is bent to press lightly against the door, as is shown in the drawing.

Now, when the door is opened, the arm *b* is of course forced backward, and as it is rigidly attached to the shaft *B*, the latter is caused to revolve more or less in its bearings.

This revolution of the shaft necessarily causes the nut to move in a vertical direction, it being prevented from revolving by means of the projection *c*, which slides in the slot *a*.

The nut, in moving upward, presses against the spring *D*, or against the weights resting upon it.

As soon, therefore, as the door is left free to move, the reaction of the spring, or the pressure of the weights, causes the nut *C* to descend rapidly, the pitch of the screw being short, to facilitate this movement, by means of which operation the screw *B* is of course turned, and its arm is caused forcibly to close the door.

By adjusting the nut *B'* up or down, the spring may be caused to bear more or less strongly upon the nut *C*.

If weights be used, a greater or less number may be employed, at will.

By the general construction herein described, a simple and efficient device is obtained, which can be cheaply constructed, and cannot readily get out of order.

It may be attached to any part of the casing, and, if desired, may be entirely concealed from view, with the exception of the arm.

Having thus fully described my invention,

What I claim as new, and desire to secure by Letters Patent, is—

The device described, consisting of the slotted plate *A*, shaft *B*, nuts *C* and *B'*, and springs *D*, or weights *E*, the whole being constructed, arranged, and operated as described, for the purpose set forth.

This specification signed and witnessed, this 4th day of January, 1869.

Witnesses:

WILLIAM DUNCAN.

E. J. DURANT,

F. A. CUSHMAN.
